UNITED STATES PATENT OFFICE.

GEORGE L. GLASER, OF NEW YORK, N. Y.

SPRAYING-NOZZLE.

996,480.

Specification of Letters Patent. Patented June 27, 1911.

Application filed May 24, 1910. Serial No. 563,073.

To all whom it may concern:

Be it known that I, GEORGE L. GLASER, a citizen of the United States, and a resident of the city of New York, borough of Brooklyn, in the county of Kings and State of New York, have invented a new and Improved Spraying-Nozzle, of which the following is a full, clear, and exact description.

The invention is an improvement in nozzles for the uniform and economical distribution of water in the form of light or heavy sprays for irrigation purposes, or for spraying water, insecticides and other liquids for agricultural, botanical and horticultural purposes, also for the equal and economical distribution of water and other liquids for fire extinguishment, and for other purposes where the spray may be advantageously used or applied. To this end the nozzle is constructed so that the liquid will issue through the spraying tip only, which tip is revolubly mounted and discharges at such an angle to its axis of revolution as to give the maximum range of distribution, and is suitably driven during the period of discharge, preferably by a motor actuated by the liquid preparatory to the ejection of the latter at the tip, whereby the liquid at the instant of its issuance from the tip is hurled from its natural linear direction into a curved path, and is disintegrated into drops or spray, the nature of either being determined by the speed, length and diameter of the tip, which speed is controlled by the character of the motor, the length of the tip and the head or pressure of the water.

Reference is to be had to the accompanying drawings forming a part of this specification, in which similar characters of reference indicate corresponding parts in all the views.

Figure 1 is a central longitudinal section through a nozzle constructed in accordance with my invention; Fig. 2 is a cross-section 45 of the same, on the line $y-y$ of Fig. 1, looking in the direction of the arrow 2, Fig. 3 is a section of the nozzle on the same line, looking in the direction of the arrow 3, and Fig. 4 is a cross-section of the nozzle on 50 the line $x-x$ of Fig. 1, looking in the direction of the arrow 4.

In the embodiment of my invention as illustrated, the nozzle comprises a body portion made up of inner and outer sections 5 and 6 respectively, a tubular stem 7 having a discharge tip 8, a motor 9, a bearing 10, a

controlling diaphragm 11 and a retaining ring 12.

The outer section 5 of the nozzle is shown to be provided with an internally-threaded 60 hose or pipe coupling 13, from which extends through the opposite end of this section, a passage 14 for the solution, this passage in some instances being of helical form, as shown. The outer section 6 of the nozzle 65 body is enlarged at its inner end and counterbored to form a shoulder 15, on which the diaphragm 11 seats, the diaphragm being suitably keyed or held against revolution when in place, by any suitable means, such 70 as a projection 16 formed thereon and extending into a recess 17 formed in the face of the shoulder. Both sections of the body of the nozzle are preferably expanded toward the center or their point of union, 75 with the inner section provided with an external flange 18 adapted to neatly fit within the counterbored portion of the outer section 6, and presenting a shoulder against which the retaining ring 12 is adapted to bear and bind the two sections firmly together and form therebetween a fluid-tight joint, the retaining ring, as shown, snugly fitting about the portion of the section 5 adjacent to the flange 18, and threaded within the 80 enlarged counterbored portion of the outer section 6. The outer section 6 of the nozzle body has an extended neck 19, in which the tubular stem 7 closely fits, and is counterbored at the base of the neck to form a suitable recess to receive the roller bearing 10, the latter, as shown, being interposed between the shoulder of the body thus formed and the shell of the motor 9, this shell being integral or otherwise rigid with the tubular 90 stem 7, and conforming to the taper of the section 6 and extending to the diaphragm 11, the shell of the motor being of a size to leave a relatively small space between it and the inner wall of the body section 6 of the 100 nozzle when the shell is firmly seated on the roller bearing, so that the entire thrust of the motor will be borne by this bearing, and, as a consequence, the friction reduced to a minimum. The motor has centrally of the 105 shell 9, a stem 20, which terminates short of the tubular stem 7, and is rigidly connected to the shell by a number of helical actuating blades or vanes 21, these blades being of any suitable number and forming in connection 110 with each other and with the stem and shell of the motor, a series of helical passages

for the solution, all discharging at the point of the stem 20 into the tubular stem 7.

The diaphragm 11 is provided at a point over the actuating vanes 21 with an opening 22 for the passage of the solution, with which the discharge end of the passage 14 is adapted to be brought into register, the passage 14 when brought over the opening, directing the flow of the solution against the 10 vanes of the motor approximately normal thereto. By loosening the retaining ring slightly, the body section 5 of the nozzle may be revolved relatively to the outer section 6, and the diaphragm 11, to cut down 15 or adjust the flow, or entirely cut it off if desired.

The discharge tip 8 of the nozzle forms a continuation of the tubular stem 7, and has its discharge end arranged at an angle of 20 approximately 45° to the axis of revolution, this angle of discharge ordinarily giving the maximum range of distribution and causes the thorough breaking up of the liquid.

25 In using the invention for irrigating purposes, a number of the nozzles are connected with a suitable source of water supply at elevated points over the area to be irrigated, the distance of these points apart depending 30 primarily on the water pressure, the flow of the water through each of the nozzles being adjusted as heretofore indicated, to give the character of the spray desired. If certain sections of the land in the irrigating 35 system only need wetting, the nozzles over other sections can be completely cut off without necessitating special valves for this purpose. The water or other solution as it passes through the motor causes the latter, 40 together with the tubular stem and tip, to be revolved at a speed depending on the pressure and the relative sizes of motor, nozzle tip, etc., and then passes through the tubular stem and the tip 8, the solution as 45 it issues from the latter being broken up by the rotary action, as before described, and projected over an area having a radius equal to the range of ejection the same as if the nozzle were stationary.

50 Having thus described my invention, I claim as new and desire to secure by Letters Patent:

1. In a nozzle for the distribution of a liquid in the form of a spray or drops, a 55 discharge tip through which the liquid is ejected into the air, revolvable about an approximately vertical axis, with the discharge end of the tip arranged at an angle to the axis of revolution to describe a cone 60 giving the maximum range of distribution, and a motor to actuate the tip, driven by the liquid which passes through the tip.

2. In a nozzle for the distribution of a 65 liquid in the form of a spray or drops, a discharge tip through which the liquid is

ejected into the air, revolvable about an approximately vertical axis, with the discharge end of the tip oblique to the axis of revolution and describing in action an inverted cone, and a motor driving the tip 70 and actuated by the liquid discharged through the tip.

3. In a nozzle for the distribution of a liquid in the form of a spray or drops, a discharge tip through which the liquid is ejected 75 into the air, revolvably mounted, with the discharge end of the tip arranged at an angle to the axis of revolution to give the maximum range of distribution, and a motor to actuate the tip, revolvably therewith 80 and driven by the liquid which passes through the tip.

4. In a nozzle for the distribution of a liquid in the form of a spray or drops, a discharge tip through which the liquid is ejected into the air, forming the sole outlet of the nozzle, said tip revolvably supported on the nozzle, with its discharge end arranged oblique to the axis of revolution, 85 and a motor to revolve the tip directly connected thereto and actuated by the liquid preparatory to its ejection through the tip.

5. In a nozzle for the distribution of a liquid in the form of a spray or drops, a nozzle body, a motor revolvable in the body, 95 a tubular stem rigid with and leading from the motor, and a discharge tip forming an extension of the stem, with its discharge end arranged at an angle to the longitudinal axis of the stem.

100 6. In a nozzle for the distribution of a liquid in the form of a spray or drops, a nozzle body of two sections, a diaphragm arranged between the sections of the body and having an opening for the passage of the liquid, the inner section of the nozzle having a coupling and provided with a passage extending therethrough from the coupling and movable into and out of register with the opening in the diaphragm, a motor arranged in the outer section of the nozzle body, having blades operatively arranged with respect to the opening in the diaphragm, and a tubular stem leading from the discharge end of the motor, having a 110 discharge tip to eject the liquid into the air.

115 7. In a nozzle for the distribution of a liquid in the form of a spray or drops, a nozzle body composed of an inner and an outer section, one of said sections having an enlarged end portion, the other of said sections having a flange fitting within the said enlarged end portion, a retaining ring surrounding the last-named section of the nozzle body and threaded into the enlarged 120 end of the first-named section and adapted to bear on said flange and detachably secure the two sections of the body together, the inner of said sections having a coupling and provided with a passage for the liquid, ex- 125 130

tending therethrough from the coupling, the outer of the said sections having a revoluble motor, a tubular stem extending from the motor and into which the liquid from the 5 motor is discharged, and a discharge tip to eject the liquid into the air, extending from the stem.

8. In a nozzle for the distribution of a liquid in the form of a spray or drops, a 10 nozzle body composed of an inner and an outer section, the inner section having a coupling, with a passage for the liquid extending therethrough from the coupling, a diaphragm arranged between the two sections 15 of the body, having an opening adapted to register with the said passage, the outer section of the body rotatably adjustable relatively to the inner section to control the flow of the liquid through the nozzle, a tubular 20 stem leading from the outer section of the nozzle, having a discharge tip to eject the

liquid into the air, a motor revoluble within the outer section of the nozzle body and secured to and discharging into said stem, and a roller bearing arranged to take the end 25 thrust incident to the operation of the motor.

9. In a nozzle for the distribution of a liquid in the form of a spray or drops, a revoluble motor arranged to be actuated by the liquid, a tubular stem extending from 30 the discharge end of the motor and rigid therewith, and a discharge tip forming a continuation of the stem, with the discharge end of the tip arranged at an angle of approximately 45° to the axis of revolution. 35

In testimony whereof I have signed my name to this specification in the presence of two subscribing witnesses.
